(57) **CLAIM**

The ornamental design for a dental appliance storage box, as shown and described.

DESCRIPTION

FIG. 1 is a front and right perspective view of a dental appliance storage box showing our new design;

FIG. 2 is a rear and left perspective view thereof;

FIG. 3 is a bottom and rear perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is a front perspective view thereof, shown in an assembled state.

The dash-dash broken lines in the drawings depict the portions of the dental appliance storage box which form no part of the claimed design.
